Fig. 1.

FIG. 1 is a perspective view of a pneumatic tire showing my new design, it being understood that the shaded tread and buttress portions continue throughout the circumference of the tire and that the shaded buttress pattern is the same on both sides of the tire;

FIG. 2 is an enlarged, fragmentary plan view of the tread of FIG. 1;

The characteristic feature of my design resides in the tread and buttress pattern extending from one sidewall of the tire to the other and shaded in FIG. 1.
